(57) **ABSTRACT**

A sound control device mounted in a vehicle and control method include measuring a drive signal input to a speaker, wherein the drive signal is generated in response to an input signal including at least one of a noise control signal and an audio signal, estimating a state of a voice coil of the speaker including at least one of displacement and temperature of the voice coil, based on the drive signal and a model of the speaker, and adjusting the input signal based on the state of the voice coil.

SOUND CONTROL DEVICE OF VEHICLE AND CONTROL METHOD THEREOF**CROSS-REFERENCE TO RELATED APPLICATION**

The present application claims priority to Korean Patent Application No. 10-2021-0188379, filed on Dec. 27, 2021, the entire contents of which is incorporated herein for all purposes by this reference.

BACKGROUND OF THE PRESENT DISCLOSURE**Field of the Present Disclosure**

The present disclosure relates to a sound control device and a control method thereof.

Description of Related Art

The content described below merely provides background information related to the present disclosure and does not form the related art.

When a vehicle is traveling, noise occurs due to air and structural noise of the vehicle. For example, noise generated by an engine of a vehicle, noise generated by friction between the vehicle and a road surface, vibration transmitted through a suspension device, wind noise generated by wind, etc. are generated.

As a method for reducing such noise, there are a passive noise control method of installing a sound absorbing material that absorbs noise inside a vehicle, and an active noise control (ANC) method of using a noise control signal having a phase opposite to the phase of the noise.

Because the passive noise control method has limitations in adaptively removing various noises, research on the active noise control method is being actively conducted. A road-noise active noise control (RANC) method for removing road noise of a vehicle is attracting attention.

To perform active noise control, an audio system of the vehicle generates a noise control signal which has the same amplitude as an internal noise of the vehicle and has a phase opposite to the phase of the internal noise, and outputs the noise control signal to the interior of the vehicle to cancel the internal noise.

The audio system of the vehicle can reproduce audio as well as eliminate the internal noise of the vehicle. For example, the audio system of the vehicle can output an audio signal related to music simultaneously with a noise control signal. Accordingly, an occupant can listen to only music without road noise.

However, because a conventional audio system simply mixes the noise control signal and the audio signal and outputs the mixed signal without considering other limitations, it may be difficult to efficiently eliminate noise or may cause a new problem.

For example, in-vehicle noise may include low-frequency components of a magnitude that a speaker cannot output depending on a road surface. Because the noise control signal for eliminating noise has the same frequency distribution as the noise, the noise control signal may also include low-frequency components of a magnitude that the speaker cannot output. Nevertheless, when the audio system controls the speaker to output the noise control signal outside the output range of the speaker, due to non-linearity or saturation of the speaker, the low-frequency components of the

noise control signal may be distorted and output or noise control performance of other frequency band signals of the noise control signal may deteriorate.

For example, a loudspeaker may have non-linear characteristics by design and may generate harmonic waves, intermodulation components, and modulation noise. Such non-linear distortion may degrade audio quality or reduce noise control performance. The smaller the size of the speaker, the greater the non-linear distortion. As another example, since the displacement characteristic of a voice coil in the loudspeaker varies according to the temperature of the loudspeaker, distortion due to temperature may occur.

The information included in this Background of the present disclosure is only for enhancement of understanding of the general background of the present disclosure and may not be taken as an acknowledgement or any form of suggestion that this information forms the prior art already known to a person skilled in the art.

Various aspects of the present disclosure are directed to providing a method for controlling a sound control device mounted in a vehicle. The method includes measuring a drive signal input to a speaker, wherein the drive signal is generated in response to an input signal including at least one of a noise control signal and an audio signal, estimating a state of a voice coil of the speaker including at least one of displacement and temperature of the voice coil, based on the drive signal and a model of the speaker, and adjusting the input signal based on the state of the voice coil.

According to at least another aspect, the present disclosure provides sound control device mounted in a vehicle. The sound control device includes a receiving unit configured to receive an input signal including at least one of a noise control signal and an audio signal, a measuring unit configured to measure a drive signal input to a speaker, wherein the drive signal is generated in response to the input signal, and an estimating unit configured to estimate a state of a voice coil of the speaker including at least one of displacement and temperature of the voice coil, based on the drive signal and a model of the speaker, and an adjusting unit configured to adjust the input signal based on the state of the voice coil.

The methods and apparatuses of the present disclosure have other features and advantages which will be apparent from or are set forth in more detail in the accompanying drawings, which are incorporated herein, and the following Detailed Description, which together serve to explain certain principles of the present disclosure.

BRIEF DESCRIPTION OF THE DRAWINGS

FIG. 1 is a schematic diagram illustrating components of a vehicle according to an exemplary embodiment of the present disclosure.

FIG. 2 is a block diagram illustrating components of an audio system according to an exemplary embodiment of the present disclosure.

FIG. 3 is a cross-sectional view for explaining displacement of a speaker according to an exemplary embodiment of the present disclosure.

FIG. 4 is a diagram for explaining a process of generating a noise control signal according to an exemplary embodiment of the present disclosure.

FIG. 5 is a block diagram illustrating the configuration of a sound control device according to an exemplary embodiment of the present disclosure.

FIG. 6 is a flowchart illustrating a method for controlling the sound control device according to an exemplary embodiment of the present disclosure.

It may be understood that the appended drawings are not necessarily to scale, presenting a somewhat simplified representation of various features illustrative of the basic principles of the present disclosure. The specific design features of the present disclosure as disclosed herein, including, for example, specific dimensions, orientations, locations, and shapes will be determined in part by the particularly intended application and use environment.

In the figures, reference numbers refer to the same or equivalent parts of the present disclosure throughout the several figures of the drawing.

DETAILED DESCRIPTION

Reference will now be made in detail to various embodiments of the present disclosure(s), examples of which are illustrated in the accompanying drawings and described below. While the present disclosure(s) will be described in conjunction with exemplary embodiments of the present disclosure, it will be understood that the present description is not intended to limit the present disclosure(s) to those exemplary embodiments of the present disclosure. On the other hand, the present disclosure(s) is/are intended to cover not only the exemplary embodiments of the present disclosure, but also various alternatives, modifications, equivalents and other embodiments, which may be included within the spirit and scope of the present disclosure as defined by the appended claims.

Hereinafter, various exemplary embodiments of the present disclosure are described with reference to the drawings. It should be noted that in giving reference numerals to components of the accompanying drawings, the same or equivalent components are denoted by the same reference numerals even when the components are illustrated in different drawings. In describing the present disclosure, when determined that a detailed description of related known functions or configurations may obscure the subject matter of the present disclosure, the detailed description thereof has been omitted.

Furthermore, in describing the components of the present disclosure, terms such as first, second, A, B, (a), (b), etc. may be used. These terms are used only to distinguish any component from other components, and features, sequences, or the like, of corresponding components are not limited by these terms. Throughout the present specification, unless explicitly described to the contrary, "including" and "comprising" any components should be understood to imply the inclusion of other elements rather than the exclusion of any other elements. A term, such as "part," "module," or the like described in the specification, means a unit of processing at least one function or operation and may be implemented as hardware or software or a combination of hardware and software. When a component, device, element, or the like of the present disclosure is described as having a purpose or performing an operation, function, or the like, the component, device, or element should be considered herein as being "configured to" meet that purpose or to perform that operation or function.

Hereinafter, it is premised that the forward vehicle is in a stationary state, such as a parked state, or that a relative speed of the forward vehicle is close to zero in relation to a

vehicle provided with a collision avoidance device of the present disclosure. In the instant case, the effect of reducing the possibility of collision by the collision avoidance device and method according to an exemplary embodiment of the present disclosure may be maximized.

The present disclosure provides an active noise control method and device configured for improving the performance of the active noise control and audio quality in consideration of the relationship between a noise control signal and an audio signal, the characteristics of a noise signal, the characteristics of a speaker, and the like.

Furthermore, the present disclosure provides a sound control device and a control method thereof for extending an output range of a speaker by adjusting an input signal so that a bias of a voice coil included in the speaker is corrected.

Furthermore, the present disclosure provides a sound control device and a control method thereof for preventing an increase in the non-linearity between a drive signal and a displacement of a voice coil depending on the temperature of the voice coil by adjusting an input signal in accordance with the temperature of the voice coil.

Furthermore, the present disclosure provides a sound control device and a control method thereof for preventing a speaker from being damaged by an excessive input signal, by limiting the input signal based on the maximum permissible displacement of a voice coil.

FIG. 1 is a schematic diagram illustrating components of a vehicle according to an exemplary embodiment of the present disclosure.

Referring FIG. 1, a vehicle 10 includes wheels 100, a suspension device 110, accelerometers 120, a microphone 130, a controller 140, a speaker 150, and an axle 160. The number and the arrangement of the components shown in FIG. 1 in an exemplary embodiment are exemplified for illustrative purpose only, and may vary in another exemplary embodiment of the present disclosure.

The vehicle 10 includes a chassis on which accessories necessary for traveling are mounted, and an audio system that performs an active noise control.

The chassis of the vehicle 10 includes front wheels respectively provided on the left and right sides of the front of the vehicle 10 and rear wheels respectively provided on the left and right sides of the rear of the vehicle 10. The chassis of the vehicle 10 further includes an axle 160 as a power transmission unit. The chassis of the vehicle 10 also includes a suspension device 110. Furthermore, the vehicle 10 may further include at least one of a power unit, a steering unit, or a braking unit. Also, the chassis of the vehicle 10 may be coupled to a body of the vehicle 10.

The suspension device 110 is a device configured for alleviating vibration or impact of the vehicle 10. A vibration due to a road surface is applied to the vehicle 10 while the vehicle 10 is traveling. The suspension device 110 alleviates vibration applied to the vehicle 10 using a spring, an air suspension, or the like. The suspension device 110 may improve the riding comfort of an occupant in the vehicle 10 through shock mitigation.

However, noise due to the suspension device 110 may be generated in the interior of the vehicle 10. Although the suspension device 110 can alleviate a large vibration applied to the vehicle 10, it is difficult to remove a minute vibration generated by the friction between the wheels 100 and the road surface. Such minute vibrations generate noise in the interior of the vehicle 10 through the suspension device 110.

Furthermore, noise generated by the friction between the wheels 100 and the road surface, noise generated by an

engine, which is a power device, or wind noise generated by wind, etc. may flow into the interior of the vehicle 10.

To eliminate the internal noise of the vehicle 10, the vehicle 10 may include an audio system.

The audio system of the vehicle 10 may predict the internal noise from the vibration of the vehicle 10, and remove the internal noise of the vehicle 10 using a noise control signal which has the same amplitude as the amplitude of the noise signal with respect to the internal noise of the vehicle 10 and has a phase opposite to the phase of the noise signal.

To the present end, the audio system includes an accelerometer 120, a microphone 130, a controller 140, and a speaker 150. The audio system may further include an amplifier (AMP).

The accelerometer 120 measures acceleration or vibration of the vehicle 10 and transmits a reference signal representing an acceleration signal to the controller 140. The reference signal is used to generate a noise control signal.

The accelerometer 120 may measure vibration generated by the friction between the wheels 100 and the road surface. To the present end, the accelerometer 120 may be provided on the suspension device 110, a connecting mechanism connecting the wheels 100 and the axle 160, or a vehicle body.

The accelerometer 120 transmits a reference signal as an analog signal to the controller 140. Otherwise, the accelerometer 120 may convert the reference signal into a digital signal and transmit the converted digital signal to the controller 140.

The audio system may use at least one of a gyro sensor, a motion sensor, a displacement sensor, a torque sensor, or a microphone instead of the acceleration sensor to measure the vibration of the vehicle 10. That is, the audio system may include a sensing unit, and the sensing unit may include at least one of the acceleration sensor, the gyro sensor, the motion sensor, the displacement sensor, the torque sensor, or the microphone.

The microphone 130 detects a sound in the vehicle 10 and transmits a sound signal to the controller 140. For example, the microphone 130 may detect noise in the vehicle 10 and transmit a noise signal to the controller 140.

The microphone 130 may measure a sound pressure of about 20 to 20 kHz, which is a human audible frequency band. The range of the measurable frequency of the microphone 130 may be narrower or wider.

In an exemplary embodiment of the present disclosure, the microphone 130 may measure internal noise generated by the friction between the wheels 100 and the road surface.

When the noise control signal is output to the interior of the vehicle 10, the microphone 130 may measure the noise signal remaining in the interior of the vehicle 10 in an environment in which the internal noise of the vehicle 10 decreases by the noise control signal. The remaining signal is referred to as an error signal or a residual signal. The error signal may be used as information for determining whether the noise in the vehicle 10 is normally reduced or eliminated.

When an audio signal is output to the interior of the vehicle 10, the microphone 130 may measure the error signal and the audio signal together.

The microphone 130 may be provided on a headrest of a seat, a ceiling or an internal wall of the vehicle 10. The microphone 130 may be provided in a plurality of positions, or in a form of a microphone array.

The microphone 130 may be implemented as a capacitor type sensor. To intensively measure noise, the microphone 130 may be implemented as a directional microphone.

According to an exemplary embodiment of the present disclosure, the microphone 130 may operate as a virtual microphone generated at the position of an occupant's ear by the controller 140.

According to an algorithm such as least mean square (LMS) or filtered-x least mean square (FxLMS) known in the art, the controller 140 may determine coefficients of an adaptive filter (often referred to as W-filter) based on the error signal(s) and the reference signal(s). The noise control signal may be generated by an adaptive filter based on a reference signal or a combination of reference signals. When the noise control signal is output through the speaker 150 via the amplifier, the noise control signal has an ideal waveform so that a destructive sound is generated near the occupant's ear and the microphone 130, wherein the destructive sound has the same amplitude as a road noise heard by passengers in the vehicle cabin and has an opposite phase to the phase of the road noise. The destructive sound from the speaker 150 is added together with the road noise in the vicinity of the microphone 130 in the vehicle cabin, lowering the sound pressure level due to the road noise at the present location.

The controller 140 may convert a reference signal and a noise signal, which are analog signals, into a digital signal, and generate a noise control signal from the converted digital signal.

The controller 140 transmits the noise control signal to the amplifier.

The amplifier receives the noise control signal from the controller 140 and an audio signal from an]Audio, Video, and Navigation (AVN) device.

The amplifier may mix the noise control signal and the audio signal, and output the mixed signal through a speaker. Furthermore, the amplifier may adjust the amplitude of the mixed signal using power amplifiers. The power amplifiers may include vacuum tubes or transistors for amplifying the power of the mixed signal.

The amplifier transmits the mixed signal to the speaker 150.

The speaker 150 receives the mixed signal, which is an electrical signal, from the amplifier, and outputs the mixed signal to the interior of the vehicle 10 in a form of a sound wave. Noise in the interior of the vehicle 10 may be reduced or eliminated by the output of the mixed signal.

The speaker 150 may be provided at a plurality of positions inside the vehicle 10.

The speaker 150 may output the mixed signal only to a predetermined occupant as needed. The speaker 150 may cause constructive interference or destructive interference at the position of the specific occupant's ear by outputting the mixed signals of different phases at a plurality of positions.

FIG. 2 is a block diagram illustrating components of an audio system according to an exemplary embodiment of the present disclosure.

Referring to FIG. 2, the audio system of the vehicle includes a sensor 200, a microphone 210, a controller 220, an AVN device 230, an amplifier 240, and a speaker 250. In FIG. 2, the sensor 200, the microphone 210, the controller 220, the AVN device 230, the amplifier 240, and the speaker 250 may respectively correspond to the accelerometer 120, the microphone 130, the controller 140, the AVN device, the amplifier, and the speaker 150 described with reference to FIG. 1.

Hereinafter, the noise signal may be noise measured at various positions including the position of an occupant's ear.

The noise control signal is a signal for eliminating or attenuating the noise signal. The noise control signal is a

signal that has the same amplitude as the noise signal and has an opposite phase to the phase of the noise signal.

The error signal is the residual noise measured after the noise signal is canceled by the noise control signal at the noise control point. The error signal may be measured by a microphone. When the microphone measures the error signal and the audio signal together, the audio system can identify the error signal since knowing the audio signal. In the instant case, the position of the microphone may be approximated to be the position of the occupant's ear, which is the noise control point.

Referring back to FIG. 2, the sensor 200 measures an acceleration signal of the vehicle as a reference signal. The sensor 200 may include at least one of an acceleration sensor, a gyro sensor, a motion sensor, a displacement sensor, a torque sensor, or a microphone.

The microphone 210 measures an acoustic signal in the vehicle. Here, the acoustic signal measured by the microphone 210 includes at least one of a noise signal, an error signal, or an audio signal.

When the noise control signal is being output to the interior of the vehicle, the microphone 210 may measure the error signal. When an audio signal is being output to the interior of the vehicle, the microphone 130 may measure the error signal and the audio signal together.

The controller 220 generates a noise control signal according to the reference signal. The noise control signal is a signal having the same magnitude as that of the internal noise of the vehicle, and having a phase opposite to that of the internal noise. When the noise control signal is being output, the controller 220 may generate the noise control signal based on the reference signal and the error signal. When an audio signal is being output, the controller 220 may extract an error signal from the acoustic signal measured by the microphone 210 and generate a noise control signal based on the reference signal and the error signal.

Meanwhile, in the exemplary embodiment, the magnitude of the signal may refer to any one of sound pressure, sound pressure level, energy, and power. Otherwise, the magnitude of the signal may refer to any one of an average amplitude, an average sound pressure, an average sound pressure level, an average energy, or an average power of the signal.

The controller 220 may independently control the noise control signal to be output regardless of whether the audio function of the AVN device 230 is operating. That is, the controller 220 may always operate in the driving situation of the vehicle. When the audio function of the AVN device 230 is turned on, the controller 220 may control the noise control signal and the audio signal to be output together. The controller 220 may control only the noise control signal to be output when the audio function of the AVN device 230 is turned off.

The controller 220 may be connected to other components of the audio system through an A2B (Automotive Audio Bus) interface.

Meanwhile, the AVN device 230 is provided in a vehicle and executes audio, video, and navigation programs according to a request of an occupant.

The AVN device 230 may transmit an audio signal to the amplifier 240 using an audio signal transmitter 231. The audio signal transmitted to the amplifier 240 is output to the interior of the vehicle through the speaker 250. For example, when the AVN device 230 transmits an audio signal related to music to the amplifier 240 under the control of an occupant, the amplifier 240 and the speaker 250 may reproduce music according to the audio signal. Furthermore, the AVN device 230 may provide driving information of the

vehicle, road information, or navigation information to the occupant using a video output device such as a display.

The AVN device 230 may communicate with an external device using a communication network supporting a mobile communication standard such as 3G (Generation) communication, Long Term Evolution (LTE) communication, or 5G communication. The AVN device 230 may receive information of nearby vehicles, infrastructure information, road information, traffic information, and the like through communication.

The amplifier 240 mixes the noise control signal and the audio signal, processes the mixed signal, and outputs the processed signal through the speaker 250. Otherwise, after processing the noise control signal or the audio signal, the amplifier 240 may mix the noise control signal and the audio signal.

The amplifier 240 may perform appropriate processing on the mixed signal in consideration of the characteristics of the noise control signal, the audio signal, or the speaker 250. For example, the amplifier 240 may adjust the magnitude of the mixed signal. To the present end, the amplifier 240 may include at least one amplifier.

The amplifier 240 may feedback the processed signal to the controller 220.

The amplifier 240 according to an exemplary embodiment of the present disclosure may be configured integrally with the controller 220. As an exemplary embodiment of the present disclosure, the controller 220 and the amplifier 240 are integrally configured and may be provided in a headrest of a seat.

The controller 220 may generate a noise control signal for eliminating an error signal among various sounds in the vehicle using the processed signal.

The speaker 250 receives the processed signal from the amplifier 240 and outputs the processed signal to the interior of the vehicle. The internal noise of the vehicle may be eliminated or attenuated by the output of the speaker 250. The detailed description thereof will be provided later.

The sensor 200, the microphone 210, the controller 220, the AVN device 230, the amplifier 240 and the speaker 250 may respectively correspond to the accelerometer 120, the microphone 130, the controller 140, the AVN device, the amplifier, and the speaker 150 described with reference to FIG. 1.

Meanwhile, the audio system of the vehicle may diagnose whether the components malfunction. For example, the audio system may detect abnormal signals of the components, and determine that a failure of the controller 220 or the sensor 200 occurs.

Hereinafter, the components of the controller 220 and the amplifier 240 will be described in detail.

The controller 220 includes at least one of a first filter unit 221, a first analog-digital converter (ADC) 222, a second filter unit 223, a second ADC 224, or a control signal generator 225 and a control signal transmitter 226. The controller 220 may be implemented with at least one digital signal processor (DSP).

The first filter unit 221 filters a reference signal of the sensor 200. The first filter unit 221 may filter a signal of a specific band in the frequency band of the reference signal. For example, to filter the reference signal of a low frequency band, which is a major noise source in the vehicle, the first filter unit 221 may apply a low pass filter to the reference signal. Besides, the first filter unit 221 may apply a high pass filter to the reference signal.

The first ADC 222 converts a reference signal, which is an analog signal, into a digital signal. The first ADC 222 may

convert the reference signal filtered by the first filter unit 221 into a digital signal. To the present end, the first ADC 222 may perform sampling on the reference signal. For example, the first ADC 222 may sample the reference signal at a sampling rate of 2 kHz. In other words, the first ADC 222 may apply down-sampling to the noise control signal. The first ADC 222 may convert the reference signal, which is an analog signal, into a digital signal by sampling the reference signal at an appropriate sampling rate.

The second filter unit 223 filters an acoustic signal of the microphone 210. The acoustic signal includes at least one of a noise signal, an error signal, or an audio signal. The second filter unit 223 may filter a signal of a specific band in the frequency band of the acoustic signal. For example, to filter the acoustic signal of the low frequency band, the second filter unit 223 may apply a low-pass filter to the acoustic signal. Besides, the second filter unit 223 may apply a high pass filter or a notch filter to the acoustic signal.

The second ADC 224 converts an acoustic signal, which is an analog signal into a digital signal. The second ADC 224 may convert the acoustic signal filtered by the second filter unit 223 into a digital signal. To the present end, the second ADC 224 may perform sampling on the acoustic signal. For example, the second ADC 224 may sample the acoustic signal at a sampling rate of 2 kHz. In other words, the second ADC 224 may apply down-sampling to the acoustic signal. The second ADC 224 may convert the acoustic signal, which is an analog signal, into a digital signal by sampling the acoustic signal at an appropriate sampling rate. Thereafter, the acoustic signal converted to the digital signal may be filtered by a high-pass filter.

Meanwhile, in FIG. 2, the first ADC 222 and the second ADC 224 are illustrated as being included in the controller 220. However, as an exemplary embodiment of the present disclosure, the first ADC 222 and the second ADC 224 may respectively be included in the sensor 200 and the microphone 210. That is, a reference signal which is an analog signal may be converted into a digital signal in the sensor 200 and transmitted to the first filter unit 221 of the controller 220. Similarly, an acoustic signal which is an analog signal may be converted into a digital signal in the microphone 210 and transmitted to the second filter unit 223 of the controller 220. In the instant case, the first filter unit 221 and the second filter unit 223 may be digital filters.

The control signal generator 225 generates a noise control signal based on the reference signal converted into a digital signal. The control signal generator 225 may generate a noise control signal further based on the error signal converted into a digital signal.

According to an exemplary embodiment of the present disclosure, the control signal generator 225 may generate a noise control signal using a Filtered-x Least Mean Square (FxLMS) algorithm. The FxLMS algorithm is an algorithm for eliminating structural-borne noises of a vehicle based on a reference signal. The FxLMS algorithm is configured for using a virtual sensor. The FxLMS algorithm may control noise in consideration of a secondary path indicating a distance between the speaker 250 and the microphone 210. This will be described in detail with reference to FIG. 4.

Furthermore, the control signal generator 225 may control the noise using an adaptive control algorithm. The controller 220 may use various algorithms such as Filtered-input Least Mean Square (FxLMS), Filtered-input Normalized Least Mean Square (FxNLM), Filtered-input Recursive Least Square (FxRLS), and Filtered-input Normalized Recursive Least Square (FxNRLS).

The control signal generator 225 may receive a feedback signal processed by the amplifier 240 and generate a noise control signal that does not affect the output of the audio signal in consideration of the processed signal of the amplifier 240. The microphone 210 may measure the error signal and the audio signal together. In the instant case, the control signal generator 225 may extract an error signal from the acoustic signal using the processed signal of the amplifier 240, and generate a noise control signal based on the extracted error signal and the reference signal. The generated noise control signal cancels out noise in the vehicle, but does not attenuate the audio signal.

The control signal transmitter 226 transmits the noise control signal generated by the control signal generator 225 to the amplifier 240.

The amplifier 240 includes at least one of a control buffer 241, a pre-processing unit 242, a first attenuation unit 243, an audio buffer 244, an equalizer 245, a calculation unit 246, and a second attenuation unit 247, a post-processing unit 248, or a Digital-Analog Converter (DAC) 249. The amplifier 240 may be implemented using at least one digital signal processor.

The control buffer 241 temporarily stores the noise control signal received from the controller 220. The control buffer 241 may transmit the noise control signal when the accumulated number of the noise control signal satisfies a predetermined condition. Otherwise, the control buffer 241 may store the noise control signal and transmit the noise control signal at regular time intervals. The control buffer 241 transmits the noise control signal to the pre-processing unit 242 and the calculation unit 246.

The pre-processing unit 242 applies up-sampling or filtering to the noise control signal received from the control buffer 241. For example, the pre-processing unit 242 may up-sample the noise control signal at a sampling rate of 48 kHz. The pre-processing unit 242 may improve the control precision for the noise control signal through upsampling. Furthermore, when the noise control signal received from the controller 220 includes noise, the pre-processing unit 242 may eliminate the noise of the noise control signal through frequency filtering. The pre-processing unit 242 transmits the preprocessed noise control signal to the first attenuator 243.

The audio buffer 244 temporarily stores the audio signal received from the AVN device 230. The audio buffer 244 may transmit the audio signal when the accumulated number of the audio signal satisfies a predetermined condition. Otherwise, the audio buffer 244 may store the audio signal and transmit the audio signal at regular time intervals. The audio buffer 244 passes the audio signal to the equalizer 245.

The equalizer 245 adjusts the audio signal for each frequency band. The equalizer 245 may divide the frequency band of the audio signal into a plurality of frequency bands, and may adjust the amplitude or phase of the audio signals corresponding to each frequency band. For example, the equalizer 245 may emphasize the audio signal of the low frequency band weakly adjust the audio signal of the high frequency band. The equalizer 245 may adjust the audio signal according to the control of an occupant. The equalizer 245 transmits the adjusted audio signal to the calculation unit 246.

The calculation unit 246 determines a control parameter based on the noise control signal received from the control buffer 241 and the audio signal received from the equalizer 245.

The calculation unit 246 may determine control parameters based on a relationship between the noise control

signal and the audio signal, a characteristic of the speaker **250**, a characteristic of a noise signal or a characteristic of an error signal, and the like.

The control parameters may include a first attenuation coefficient for the noise control signal or a second attenuation coefficient for the audio signal. Furthermore, the control parameters may include limit values for the range of the noise control signal or the audio signal. Besides, the control parameters may include various parameter values for active noise control.

The first attenuation unit **243** applies the first attenuation coefficient determined by the calculation unit **246** to the noise control signal, and transmits the attenuated noise control signal to the post-processing unit **248**. When the first attenuation coefficient is not determined by the calculation unit **246**, the first attenuation unit **243** passes the noise control signal.

The second attenuation unit **247** applies the second attenuation coefficient determined by the calculation unit **246** to the audio signal, and transmits the attenuated audio signal to the post-processing unit **248**. When the second attenuation coefficient is not determined by the calculation unit **246**, the second attenuation unit **247** passes the audio signal.

The noise control signal and the audio signal are mixed while being transmitted to the post-processing unit **248**. That is, the mixed signal is input to the post-processing unit **248**.

The post-processing unit **248** performs at least one of linearization or stabilization on the mixed signal. Here, the linearization and the stabilization are to post-process the mixed signal based on the mixed signal of the speaker **250** and the displacement limit.

The DAC **249** converts the post-processed signal which is a digital signal into an output signal which is an analog signal. The DAC **249** transmits the output signal to the speaker **250**.

The speaker **250** outputs the output signal received from the DAC **249** in a form of sound waves. The speaker **250** may output the output signal to the interior of the vehicle. The output signal eliminates the noise inside the vehicle while audio according to the audio signal may be output to the interior of the vehicle.

Meanwhile, although it has been described with reference to FIG. 2 that the reference signal and the noise control signal are singular, they may be plural. For example, the controller **220** may obtain reference signals from a plurality of sensors and obtain a plurality of error signals from a plurality of microphones. Furthermore, the controller **220** may generate a plurality of noise control signals and output the plurality of noise control signals through a plurality of speakers.

Furthermore, the controller **220** may control the noise for each seat. For example, the controller **220** may obtain reference signals from a plurality of sensors, obtain error signals from the microphones provided close to the position of a driver's ear, and generate the noise control signals output from the respective speakers based on a plurality of secondary paths from the points at which the noise control signals are generated to the position of the driver's ear through the plurality of speakers.

FIG. 3 is a cross-sectional view for explaining displacement of a speaker according to an exemplary embodiment of the present disclosure.

Referring to FIG. 3, the speaker **30** includes a lower plate **300**, a magnet **310**, an upper plate **320**, a voice coil **330**, a pole piece **340**, and a suspension **350**, a frame **360**, a cone **370**, a surround **380**, and a dust cap **390**.

Although the speaker **30** is expressed as a loudspeaker of a moving coil type in FIG. 3, the speaker **30** may be implemented as a speaker of another type.

The speaker **30** includes a lower plate **300**, an upper plate **320**, and a magnet **310** provided between the lower plate **300** and the upper plate **320**. The lower plate **300** includes a pole piece **340** with a protruding center portion.

The magnet **310** and the upper plate **320** may be formed in an annular shape surrounding the pole piece **340**. Furthermore, the voice coil **330** may be provided in a gap space between the pole piece **340** and the upper plate **320**, and the voice coil **330** may be provided to be wound around the pole piece **340**. The voice coil **330** is attached to a bobbin, and the bobbin may be fixed to the frame **360** through the suspension **350** having elasticity. The suspension **350** has a flexible property and may return the position of the voice coil **330**.

The lower plate **300**, the magnet **310**, the upper plate **320**, the voice coil **330**, and the pole piece **340** form a magnetic circuit. The magnet **310** may be ferrite. When an alternating current is applied to the voice coil **330**, the voice coil **330** generates a magnetic field. Here, the alternating current may be an output signal output by the amplifier. The pole piece **340** concentrates the magnetic field generated by the voice coil **330**. The magnetic field generated by the voice coil **330** interacts with the magnetic field of the magnet **310**. Due to the present interaction, the voice coil **330** moves up and down. The force generated by the interaction between the DC magnetic flux of the magnet **310** and the AC magnetic flux of the voice coil **330** vibrates the voice coil **330** and the cone **370** to generate a sound. The movement of the voice coil **330** is referred to as displacement or excursion. The voice coil **330** generates vibration or oscillation in the cone **370** through the bobbin.

The cone **370** is connected to the frame **360** through the surround **380** having elasticity and vibrates by the voice coil **330**. The cone **370** generates a sound while pushing air through vibration.

The dust cap **390** protects the cone **370** from foreign substances.

Meanwhile, the displacement of the voice coil **330** is determined based on various parameters including the magnitude of the alternating current applied to the voice coil **330**.

The displacement of the voice coil **330** has a physical limit due to the structure of the speaker **30**. Furthermore, the displacement of the voice coil **330** in the speaker **30** may be limited by an external environment such as distortion of an input signal, heat generation, aging, or temperature of the speaker **30**. The displacement of the voice coil **330** may be within a permissible displacement range by the output signal applied to the voice coil **330**, but on the other hand, the displacement of the voice coil **330** may be outside the permissible displacement range by the output signal. This is called a saturation state. In the instant case, a signal to be output by the speaker **30** may be distorted or malfunction of the speaker **30** may occur.

To solve the above problem of the speaker **30**, the amplifier according to an exemplary embodiment of the present disclosure may perform linearization and stabilization. The amplifier may apply linearization and stabilization to the output signal applied to the voice coil **330**.

The linearity of the speaker **30** means a linear relationship between the input signal of the speaker **30** and the displacement of the voice coil **330**. Within the linear range of the voice coil **330**, the displacement of the voice coil **330** may vary linearly with the magnitude of the input signal. On the other hand, when the voice coil **330** operates outside the

linear range by the input signal of the speaker 30, the displacement of the voice coil 330 may not vary linearly with the magnitude of the input signal. In the instant case, the amplifier may control such that the linearity between the input signal and the displacement of the voice coil 330 is maintained outside the linear range of the voice coil 330.

The stabilization of the speaker 30 means correcting an eccentric position of the voice coil 330. The voice coil 330 may not be located at the precise center of the operating range. For example, the voice coil 330 may vibrate while its position is eccentric downward. In the instant case, the downward movement of the voice coil 330 may be restricted. At the instant time, the amplifier may apply an offset to the input signal of the speaker 30 in consideration of the eccentric position and the center of displacement of the voice coil 330.

The amplifier may maintain linearity between displacements of the voice coil 330 and maintain the center of the voice coil 330 by use of linearization and stabilization.

Meanwhile, when outputting sound pressure of the same magnitude, it is more difficult for the speaker 30 to output a low frequency signal than a high frequency signal. The sound pressure representing the force pushing the air is proportional to the acceleration of the cone 370. When the input signal is a low frequency signal, the acceleration of the cone 370 according to the low frequency signal is lower than the acceleration of the cone 370 according to the high frequency signal. Accordingly, it is more difficult for the speaker 30 to output a low frequency signal than a high frequency signal.

To output a low frequency signal having the same sound pressure level as the sound pressure level of a high frequency signal, there is a method of making the amplitude of the low frequency signal greater than the amplitude of the high-frequency signal. In the instant case, however, the speaker 30 may malfunction due to heat generation of the voice coil 330 or excessive displacement of the voice coil 330. In the case of the excessive displacement of the voice coil 330, the low frequency signal may be distorted due to non-linearity within the speaker 30. Accordingly, the speaker 30 outputs an abnormal sound.

Furthermore, there is a method of increasing the size of the speaker 30 to output a low frequency signal having the same sound pressure level as the sound pressure level of a high frequency signal. As the size of the cone 370 is increased, the cone 370 can push an increased amount of air. However, there is a limit to installing a large speaker in a vehicle. When the speaker 30 is small like a headrest speaker, it is difficult for the speaker 30 to output a low frequency signal having a range of 20 to 500 kHz, which is the main frequency band of the noise control signal. When the audio system tries to forcibly output a low frequency signal which is difficult for the speaker 30 to output through the speaker 30, not only the low-frequency signal but also other signals within the frequency band of the low frequency signal may be distorted due to the non-linearity or saturation of the speaker 30.

When the audio system tries to forcibly output a low-frequency signal which is difficult to be output by the speaker 30 through the speaker 30, not only the low frequency signal but also other signals within the low frequency band may be distorted.

The audio system according to an exemplary embodiment of the present disclosure can reduce distortion due to the low frequency signal by adjusting the low frequency signal in

consideration of the low frequency response characteristic according to the size of the speaker 30. The details will be described later.

FIG. 4 is a diagram for explaining a process of generating a noise control signal according to an exemplary embodiment of the present disclosure.

Referring to FIG. 4, a microphone 210, a controller 220, and a speaker 250 are illustrated.

According to an exemplary embodiment of the present disclosure, the audio system of the vehicle may eliminate the noise in the vehicle by outputting a noise control signal which is generated based on a reference signal measured by the sensor 200. Furthermore, the audio system may use residual noise remaining after noise cancellation as feedback to maximally eliminate residual noise of the vehicle.

Vibration is generated by friction between the vehicle and the road surface while the vehicle is traveling, and the generated vibration causes noise inside the vehicle.

The controller 220 obtains a reference signal detected by the sensor 200 and predicts a noise signal inside the vehicle based on the reference signal. The controller 220 generates a noise control signal for eliminating the predicted noise signal. The noise control signal is a signal having the same amplitude as that of the noise signal, but having an opposite phase to the phase of the noise signal. The controller 220 outputs a noise control signal through the speaker 250.

In the instant case, a path from the point where the noise signal inside the vehicle is generated to the point where the noise signal is eliminated or attenuated by the noise control signal is referred to as a primary path or a main acoustic path. The primary path may be modeled as a path between the sensor 200 and the speaker 250. In consideration of a transfer function and delay time for the primary path, the controller 220 may generate the noise control signal. In consideration of the transfer function of the primary path, the controller 220 may predict the noise signal at the position of the speaker 250 from the reference signal of the sensor 200, and generate a noise control signal based on the predicted noise signal.

In spite of the output of the noise control signal to eliminate the noise signal, residual noise may remain at the listening position of an occupant. For example, residual noise may be generated because the noise control signal output from the speaker 250 varies while propagating to the listening position of the occupant. For example, the noise control signal may vary by a secondary path such as attenuation due to spatial propagation, noise interference, speaker performance, an ADC, or a DAC. Otherwise, because the noise control signal generated by the controller 220 varies while passing through the amplifier or the speaker 250, residual noise may occur at the listening position of the occupant. Such residual noise may be expressed as an error signal representing the sum of the noise signal and the varied noise control signal at the listening position of the occupant.

For precise noise cancellation, after the noise control signal is output to the interior of the vehicle, the microphone 210 may measure the residual noise inside the vehicle. When the microphone 210 is provided adjacent to the position of the occupant's ear, the error signal may be measured by the microphone 210.

The controller 220 may generate a noise control signal configured for eliminating the error signal by use of the error signal as feedback.

The path from the point where the noise control signal is generated to the listening point of the occupant is referred to as a secondary path. Here, the secondary path may be modeled as a path between the speaker 250 and the microphone 210.

phone 210. The secondary path may further include a path between the controller 220 and the speaker 510. As the microphone 210 is provided closer to the listening position of the occupant, the microphone 210 can more accurately measure the error signal. The controller 220 may receive the error signal as feedback from the microphone 210 and generate the noise control signal by further considering the transfer function and the delay time for the secondary path.

The controller 220 generates the noise control signal so that the noise control signal varied by the secondary path has the same amplitude as that of the noise signal and the opposite phase to the phase of the noise signal. Accordingly, the error signal may be close to zero.

In the present way, the controller 220 may eliminate the noise signal and the residual noise.

Meanwhile, according to another exemplary embodiment of the present disclosure, the audio system of the vehicle may more accurately model the secondary path using a virtual microphone. The controller 220 may obtain information on the secondary path based on the signal measured by the virtual microphone, and may eliminate noise corresponding to the virtual secondary path.

The controller 220 generates a virtual microphone at a point where an occupant's ear is expected to be located based on information on the occupant's ear position or information on the body of the occupant. When the position of the occupant's ear is changed, the controller 220 may generate a virtual microphone based on the changed position of the occupant's ear. The virtual microphone measures the residual noise at the position of the occupant's ear as an error signal. In the instant case, the controller 220 obtains a path from the point where a virtual noise control signal is generated to the position of the virtual microphone as a virtual secondary path. The controller 220 may generate an error signal measured by the virtual microphone in consideration of the transfer function for the virtual secondary path.

The controller 220 generates a noise control signal based on the virtual error signal.

Through the above process, the audio system of the vehicle can generate a noise control signal based on the virtual secondary path that more accurately models the secondary path. Accordingly, the performance of active noise control may be improved.

FIG. 5 is a diagram illustrating the configuration of a sound control device according to an exemplary embodiment of the present disclosure.

Referring to FIG. 5, the sound control device 500 includes a receiving unit 501, an adjusting unit 503, a generating unit 505, a measuring unit 507, and an estimating unit 509.

The receiving unit 501 receives an input signal including at least one of a noise control signal or an audio signal. The receiving unit 501 may receive the noise control signal from the controller and receive the audio signal from the AVN device.

The adjusting unit 503 is configured to adjust the input signal according to the state of the voice coil included in a speaker 510.

The adjustment operation of the adjusting unit 503 may be continuously performed while an input signal is input. However, when the receiving unit 501 is configured to receive the input signal for the first time, the adjusting unit 503 may transmit the input signal to the generating unit 505 as it is without adjusting the input signal.

The generating unit 505 generates a drive signal based on the input signal or the input signal adjusted by the adjusting unit 503. Here, the drive signal includes at least one of an

input voltage or an input current input to the voice coil of the speaker 510. The generator 505 may correspond to a DAC that converts a digital signal into an analog signal.

The speaker 510 receives a drive signal and outputs a sound wave corresponding to the input signal. The drive signal transmitted to the speaker 510 is input to the voice coil to generate magnetic flux. The cone included in the speaker 510 generates sound waves while moving in response to the magnetic flux. Accordingly, the speaker 510 may output the input signal in a form of sound waves. The speaker 510 may be referred to as a transducer.

The measuring unit 507 is configured to measure a drive signal input to the speaker 510, wherein the drive signal is generated in response to the input signal. That is, the measuring unit 507 measures at least one of an input voltage or an input current input to the speaker 510.

The estimating unit 509 is configured to estimate the state of the voice coil based on the drive signal and the model of the speaker 510. Here, the state of the voice coil includes at least one of displacement or temperature of the voice coil. Meanwhile, the model of the speaker 510 is obtained by modeling the relationship between various components such as an input signal, the displacement of the voice coil, the temperature of the voice coil, a force factor, the stiffness of the suspension of the speaker 510, electrical inductance, and the like. Here, the force factor represents a factor multiplied by a magnetic field in an air gap of the voice coil and a length of the voice coil belonging to the magnetic field. Because the model of the speaker 510 is obvious to those skilled in the art of the speaker 510, a detailed description of the model of the speaker 510 will be omitted.

Furthermore, the estimating unit 509 may estimate a center of displacement of the voice coil. Here, the center of the displacement of the voice coil indicates the position of the voice coil when the voice coil does not move. As an exemplary embodiment of the present disclosure, the estimating unit 509 may estimate the position of the voice coil predicted according to the model of the speaker 510 as the center of the displacement when the magnitude of the measured drive signal is 0. The estimating unit 509 may estimate whether the center of the displacement of the voice coil is biased from a preset center position using the model of the speaker 510.

The adjusting unit 503 adjusts the input signal based on the state of the voice coil. The adjusting unit 503 may adjust the input signal for at least one of stabilization control, non-linear control, or protection control.

According to an exemplary embodiment of the present disclosure, the adjusting unit 503 may adjust the input signal to stabilize the voice coil.

The center of the displacement of the voice coil may be biased from the preset center position. Here, the preset center position of the voice coil indicates the center between one displacement limit of and the other displacement limit of the voice coil, or indicates a position set according to the design of the speaker 510. The one displacement limit of the voice coil indicates the maximum distance the voice coil can move in one direction. Alternatively, the center position may be a displacement point at which a force factor according to the displacement of the voice coil is symmetrical in the displacement-force factor graph of the voice coil.

Due to the difference between the center of the displacement and the center position of the voice coil, the one displacement limit of the voice coil may be smaller than the other displacement limit. According to the characteristics of

the voice coil moving symmetrically with respect to the center position, the operation range of the voice coil may be restricted.

When the center of the displacement of the voice coil is biased from the center position, the adjusting unit **503** may adjust the input signal depending on the distance between the center of the displacement and the center position. The adjusting unit **503** may adjust the input signal to decrease the distance between the center of the displacement and the center position.

The adjusting unit **503** may expand a physical operation range of the voice coil through stabilization of the voice coil. Accordingly, the maximum output of the speaker **510** may be increased. Even if the size of the speaker **510** is small, the maximum output and the output range of the bass of the speaker **510** may increase.

According to another exemplary embodiment of the present disclosure, the adjusting unit **503** may adjust the input signal for controlling the non-linearity of the voice coil.

The linear relationship between the drive signal input to the voice coil and the displacement of the voice coil may become non-linear depending on the temperature of the voice coil. When the magnitude of the drive signal is relatively small, the relationship between the drive signal and the displacement of the voice coil is linear. On the other hand, when the magnitude of the drive signal is relatively large, the relationship between the drive signal and the displacement of the voice coil is non-linear. That is, the relationship between the drive signal and the displacement of the voice coil may be divided into a linear section and a non-linear section in accordance with the magnitude of the drive signal. In the instant case, the linear section and the non-linear section may vary depending on the temperature of the voice coil. For example, even if a drive signal of a specific magnitude belongs to the linear section at a low temperature of the voice coil, the drive signal may belong to the non-linear section at a high temperature of the voice coil.

The adjusting unit **503** may adjust the input signal to compensate for non-linearity of the voice coil depending on the temperature of the voice coil. The adjusting unit **503** may attenuate the input signal according to an increase in the temperature of the voice coil. Conversely, the adjusting unit **503** may amplify the input signal according to a decrease in the temperature of the voice coil. That is, the adjusting unit **503** may adjust the input signal so that the linear section is maximized even when the temperature of the voice coil changes.

According to another exemplary embodiment of the present disclosure, the adjusting unit **503** may adjust a magnitude of each frequency component of the input signal. Because the magnitude of the low-frequency signal may have greater variability than the magnitude of the high-frequency signal when the temperature of the voice coil is high, the adjusting unit **503** may reduce the magnitude of the low-frequency component of the input signal more than the magnitude of the high-frequency component.

The adjusting unit **503** compensates for the non-linearity depending on the temperature of the voice coil, so that it is possible to prevent the increase in the non-linearity between the drive signal and the displacement of the voice coil depending on the temperature of the voice coil, and in the distortion of the output of the speaker **510**. By adjusting the input signal, total harmonic distortion due to the non-linear characteristic of the speaker **510** may be reduced.

Furthermore, when the temperature of the voice coil increases, the adjusting unit **503** may prevent an increase in the temperature of the voice coil by attenuating the magnitude of the input signal.

According to another exemplary embodiment of the present disclosure, the adjusting unit **503** may limit the magnitude of the input signal based on a preset maximum displacement of the voice coil. As an exemplary embodiment of the present disclosure, when the displacement of the voice coil estimated in response to the input signal exceeds the maximum displacement, the adjusting unit **503** may attenuate the overall amplitude of the input signal. As an exemplary embodiment of the present disclosure, when the displacement of the voice coil estimated in response to the input signal exceeds the maximum displacement, the adjusting unit **503** may clip the input signal based on the magnitude of the input signal corresponding to the maximum displacement.

The maximum displacement may vary depending on the size, type, characteristics, and the like of the speaker **510** and may be preset.

The adjusting unit **503** can prevent the speaker **510** from being damaged by an excessive input signal by limiting the magnitude of the input signal, and can prevent deterioration of audio quality or noise control performance due to distortion.

According to another exemplary embodiment of the present disclosure, the adjusting unit **503** may adjust the input signal, and preferentially adjust the noise control signal among the noise control signal and the audio signal included in the input signal. That is, the adjusting unit **503** may preferentially adjust the noise control signal during stabilization control for correcting bias, non-linear control depending on the temperature of the voice coil, or limit control according to the maximum displacement.

When the adjusting unit **503** preferentially adjusts the audio signal, the volume of audio that an occupant listens to is consistently changed, and the occupant may feel the deterioration of the audio quality. On the other hand, when the adjusting unit **503** preferentially adjusts the noise control signal, the occupant can listen to audio at a constant volume, and the occupant may feel a consistent audio quality. That is, the occupant may feel that the audio quality is better when the volume of the noise changes than when the volume of the audio changes.

Furthermore, due to the characteristics of the speaker **510**, it is difficult for the speaker **510** to output a noise control signal of a lower frequency band than an audio signal of an audible frequency band. That is, the speaker **510** may generate distortion in a low frequency band by the noise control signal. Accordingly, the adjusting unit **503** can reduce distortion in the low frequency band by preferentially adjusting the noise control signal.

Meanwhile, the sound control device **500** according to an exemplary embodiment of the present disclosure may correspond to the amplifier **240** in FIG. 2. The components of the sound control device **500** may be partially implemented by the components of the amplifier **240** in FIG. 2. For example, the receiving unit **501** may correspond to the control buffer **241** and the audio buffer **244**, and the adjusting unit **503** may correspond to the first attenuation unit **243**, the calculation unit **246**, the second attenuation unit **247**, and the post-processing unit **248**. The generating unit may correspond to the DAC **249**. Furthermore, the sound control device **500** may further use the pre-processing unit **242**, or the equalizer **245**.

The technical effect of the sound control device **500** may increase as the size of the speaker **510** decreases.

FIG. 6 is a flowchart illustrating a method for controlling the sound control device according to an exemplary embodiment of the present disclosure.

Referring to FIG. 6, the sound control device receives an input signal including at least one of a noise control signal or an audio signal (**S600**).

The sound control device generates a drive signal corresponding to the input signal (**S602**).

The drive signal is a signal generated in response to the input signal including at least one of a noise control signal or an audio signal. The drive signal includes at least one of an input voltage or an input current input to the speaker. This drive signal is input to the speaker, and causes the voice coil of the speaker to move.

The sound control device is configured to measure the drive signal input to the speaker (**S604**).

The sound control device estimates the state of the voice coil including at least one of a displacement or a temperature of the voice coil of the speaker, based on the drive signal and the model of the speaker (**S606**).

The sound control device adjusts the input signal based on the state of the voice coil (**S608**).

According to an exemplary embodiment of the present disclosure, the sound control device estimates the center of displacement of the voice coil. When the center of the displacement of the voice coil is biased from a preset center position, the sound control device may adjust the input signal to decrease the distance between the center of the displacement and the center position.

According to an exemplary embodiment of the present disclosure, the sound control device may limit the magnitude of the input signal based on a preset maximum displacement of the voice coil.

According to an exemplary embodiment of the present disclosure, the sound control device may adjust the input signal to compensate for non-linearity of the voice coil depending on the temperature of the voice coil. The sound control device may attenuate the input signal according to an increase in the temperature of the voice coil.

According to an exemplary embodiment of the present disclosure, the sound control device may preferentially adjust the magnitude of the noise control signal over the audio signal.

Thereafter, the sound control device generates a drive signal corresponding to the adjusted input signal (**S610**).

The sound control device reproduces the adjusted input signal by inputting the drive signal corresponding to the adjusted input signal to the speaker.

In an exemplary embodiment of the present invention, the sound control device may be implemented in a form of hardware or software, or may be implemented in a combination of hardware and software.

As described above, according to an exemplary embodiment of the present disclosure, the performance and audio quality of the active noise control may be improved in consideration of the relationship between the noise control signal and the audio signal, the characteristics of the noise signal, and the characteristics of the speaker.

According to another exemplary embodiment of the present disclosure, the output range of the speaker may extend by adjusting the input signal so that the bias of the voice coil included in the speaker is corrected.

According to another exemplary embodiment of the present disclosure, by adjusting the input signal in accordance with the temperature of the voice coil, it is possible to

prevent an increase in the non-linearity between the drive signal and the displacement of the voice coil in accordance with the temperature of the voice coil.

According to another exemplary embodiment of the present disclosure, by limiting the input signal based on the maximum permissible displacement of the voice coil, it is possible to prevent the speaker from being damaged by the excessive input signal.

According to another exemplary embodiment of the present disclosure, by preferentially adjusting the noise control signal among the noise control signal and the audio signal included in the input signal, it is possible to maintain the quality of audio that an occupant listens to.

Various implementations of the systems and techniques described herein may include digital electronic circuits, integrated circuits, field programmable gate arrays (FPGAs), application specific integrated circuits (ASICs), computer hardware, firmware, software, and/or a combination thereof.

These various implementations may include an implementation using one or more computer programs executable on a programmable system. The programmable system includes at least one programmable processor (which may be a special purpose processor or a general-purpose-processor) coupled to receive and transmit data and instructions from and to a storage system, at least one input device, and at least one output device. Computer programs (also known as programs, software, software applications or codes) include instructions for a programmable processor and are stored in a "computer-readable recording medium".

The computer-readable recording medium includes all types of recording devices in which data readable by a computer system are stored. The computer-readable recording medium may include non-volatile or non-transitory, such as ROM, CD-ROM, magnetic tape, floppy disk, memory card, hard disk, magneto-optical disk, and storage device, and may further include a transitory medium such as a data transmission medium. Furthermore, the computer-readable recording medium may be distributed in a network-connected computer system, and the computer-readable codes may be stored and executed in a distributed manner.

Although it is described that each process is sequentially executed in the flowchart/timing diagram of the exemplary embodiment, this is merely illustrative of the technical idea of an exemplary embodiment of the present disclosure. In other words, because an ordinary skilled person in the art to which the embodiments of the present disclosure pertain may make various modifications and changes by changing the order described in the flowchart/timing diagram without departing from the essential characteristics of the present disclosure or performing in parallel one or more of the steps, the flowchart/timing diagram is not limited to a time-series order.

Furthermore, the terms such as "unit", "module", etc. included in the specification mean units for processing at least one function or operation, which may be implemented by hardware, software, or a combination thereof.

For convenience in explanation and accurate definition in the appended claims, the terms "upper", "lower", "inner", "outer", "up", "down", "upwards", "downwards", "front", "rear", "back", "inside", "outside", "inwardly", "outwardly", "interior", "exterior", "internal", "external", "forwards", and "backwards" are used to describe features of the exemplary embodiments with reference to the positions of such features as displayed in the figures. It will be further understood that the term "connect" or its derivatives refer both to direct and indirect connection.

21

The foregoing descriptions of predetermined exemplary embodiments of the present disclosure have been presented for purposes of illustration and description. They are not intended to be exhaustive or to limit the present disclosure to the precise forms disclosed, and obviously many modifications and variations are possible in light of the above teachings. The exemplary embodiments were chosen and described in order to explain certain principles of the invention and their practical application, to enable others skilled in the art to make and utilize various exemplary embodiments of the present disclosure, as well as various alternatives and modifications thereof. It is intended that the scope of the present disclosure be defined by the Claims appended hereto and their equivalents.

What is claimed is:

1. A computer-implemented method for controlling a input signal of a speaker in a vehicle, the method comprising:

measuring a drive signal input to the speaker, wherein the drive signal is generated in response to the input signal including at least one of a noise control signal and an audio signal;

estimating a state of a voice coil of the speaker including at least one of displacement and temperature of the voice coil, based on the drive signal and a model of the speaker; and

adjusting the input signal based on the state of the voice coil.

2. The method of claim 1, wherein the adjusting of the input signal includes:

estimating a center of the displacement of the voice coil; and

adjusting the input signal to decrease a distance between the center of the displacement of the voice coil and a preset center position when the center of the displacement of the voice coil is biased from the preset center position, using the model of the speaker.

3. The method of claim 1, wherein the adjusting of the input signal includes:

limiting a magnitude of the input signal based on a preset maximum displacement of the voice coil.

4. The method of claim 3, further including:

when the displacement of the voice coil estimated in response to the input signal exceeds the maximum displacement, clipping the input signal based on the magnitude of the input signal corresponding to the maximum displacement.

5. The method of claim 1, wherein the adjusting of the input signal includes:

adjusting the input signal to compensate for non-linearity of the voice coil depending on the temperature of the voice coil.

6. The method of claim 5, wherein the adjusting of the input signal includes:

attenuating the input signal according to an increase in the temperature of the voice coil; and

amplifying the input signal according to a decrease in the temperature of the voice coil.

7. The method of claim 1, wherein the adjusting of the input signal includes:

adjusting a magnitude of each frequency component of the input signal.

8. The method of claim 7, wherein the adjusting of a magnitude of each frequency component of the input signal includes:

22

reducing a magnitude of a low-frequency component of the input signal more than a magnitude of a high-frequency component.

9. The method of claim 1, wherein the adjusting of the input signal includes:

adjusting a magnitude of the noise control signal among the noise control signal and the audio signal.

10. A sound control apparatus mounted in a vehicle, the sound control apparatus comprising:

at least one memory storing computer-executable instructions; and

at least one processor,

wherein the at least one processor is configured to execute the computer-executable instructions to:

receive an input signal including at least one of a noise control signal and an audio signal;

measure a drive signal input to a speaker, wherein the drive signal is generated in response to the input signal; and

estimate a state of a voice coil of the speaker including at least one of displacement and temperature of the voice coil, based on the drive signal and a model of the speaker; and

adjust the input signal based on the state of the voice coil.

11. The sound control apparatus of claim 10, wherein the at least one processor is configured to:

estimate a center of the displacement of the voice coil; and adjust the input signal to decrease a distance between the center of the displacement of the voice coil and a preset center position when the center of the displacement of the voice coil is biased from the preset center position, using the model of the speaker.

12. The sound control apparatus of claim 10, wherein in adjusting the input signal based on the state of the voice coil, the at least one processor is configured to limit a magnitude of the input signal based on a preset maximum displacement of the voice coil.

13. The sound control apparatus of claim 12, wherein in adjusting the input signal based on the state of the voice coil, the at least one processor is configured to:

conclude that the displacement of the voice coil estimated in response to the input signal exceeds the maximum displacement; and

clip the input signal based on the magnitude of the input signal corresponding to the maximum displacement.

14. The sound control apparatus of claim 10, wherein in adjusting the input signal based on the state of the voice coil, the at least one processor is configured to adjust the input signal to compensate for non-linearity of the voice coil depending on the temperature of the voice coil.

15. The sound control apparatus of claim 14, wherein the at least one processor is configured to attenuate the input signal according to an increase in the temperature of the voice coil and amplify the input signal according to a decrease in the temperature of the voice coil.

16. The sound control apparatus of claim 10, wherein in adjusting the input signal based on the state of the voice coil, the at least one processor is configured to adjust a magnitude of each frequency component of the input signal.

17. The sound control apparatus of claim 16, wherein the adjusting of a magnitude of each frequency component of the input signal includes:

reducing a magnitude of a low-frequency component of the input signal more than a magnitude of a high-frequency component.

18. The sound control device method of claim **10**, wherein the at least one processor is configured to adjust a magnitude of the noise control signal among the noise control signal and the audio signal.
